DOOR OPENING MECHANISM

Kenneth James O'Hara, Pembina, N. Dak.

Application October 16, 1934, Serial No. 748,539

2 Claims. (Cl. 268—34)

My invention relates generally to door opening and closing mechanism, and particularly to mechanism of this type especially suited to operation of garage and other similar doors by the simple expedient of running a vehicle or other suitable weight onto and from a member located in the pavement or floor, and an important object of my invention is to provide a simplified and relatively inexpensive mechanism of the character indicated.

Another important object of my invention is to provide a door opening and closing mechanism of the character indicated which does not require the presence therein of timing devices. It is also an important object of my invention to provide a mechanism of the character indicated above which is controlled and partly operated by compressed air or other suitable air under pressure. Other objects and advantages of my invention will be apparent from a reading of the following description in connection with the drawings, wherein for purposes of illustration I have shown a preferred embodiment of my invention.

In the drawings:—

Figure 1 is an elevational view of the outside of a garage or the like showing the outside of the mechanism controlled door, with parts of the mechanism in sight.

Figure 2 is a horizontal sectional view taken through Figure 1 taken approximately on the line 2—2 and looking downwardly in the direction of the arrows.

Figure 3 is a transverse vertical sectional view taken through Figure 1 approximately on the line 3—3 and looking toward the left in the direction of the arrows.

Figure 4 is a longitudinal sectional view through one of the door operating cylinders.

Figure 5 is a transverse vertical sectional view taken through the control valve.

Referring in detail to the drawings, the numeral 5 refers generally to the front of a garage or similar building having the garage door opening 6 in which the sectional door 7 is hinged, and the numeral 8 refers generally to the pavement in front of the garage and the numeral 9 to the floor of the garage, the pavement and the floor having in common a pit 10 in which works the depressible platform 11 which is located at pavement and floor level, and which operates in a manner to control the opening and closing of the door 7.

The door 7 comprises in reality a pair of doors 12 and 13. The outer edge of the door 12 is

hinged as indicated at 14 and 15 to the side of the door opening 6, while the door 13 has its outer edge hinged as indicated at 16 and 17 to the opposite side of the door opening 6 in such a way that the inner edges of the doors 12 and 13 meet.

Each of the doors 12 and 13 is composed of a pair of sections 18, 19 and 20, 21, respectively. While the hinges 14 and 15 and 16 and 17 are attached to the outer side of the door frame and to the outer side of the door 12 and 13, the hinges 22, 23 and 24, 25 connecting the adjacent edges of the sections 18, 19, and 20, 21 are attached to the inner side of the sections.

All of the hinges mentioned are of the spring type with the springs arranged to swing the door sections relative to each other and the doors relative to the door frame, and the springs are so tensioned that when free to do so, the door sections will be swung toward the closed position, and compressed air operated means about to be described is utilized to overcome tension of these spring hinges for opening the doors.

Fixed to the section 18 of the door 12 and to the section 21 of the door 13 at the top thereof is a pivot bracket 26, 27, respectively, on which is pivotally connected the end of the corresponding connecting rod 28, 28' of the respective compressed air cylinders 29, 29' which are identical in construction but oppositely arranged on a level with the upper end of the brackets 26, 27 and in positions on the front wall of the garage outwardly of the sides of the door opening as clearly shown in Figures 1 and 2.

Each of the cylinders 29, 29' consists of a closed end cylinder having on the closed end the spaced lugs 30 having the registering pivot holes 31 to pass the pivot 32 which passes also through an appropriate bracket 33, 33', respectively, projecting from the front of the front wall of the garage as indicated. The opposite end of the cylinder is closed by a threaded head 34 containing a piston rod packing 35 of suitable type and a nipple 36 which has a passage 37 communicating with the interior of the cylinder 29' at one side of the piston 38 with which the connecting rod 28' is connected as shown in Figure 4. It is obvious that the pivotal mounting of the cylinders 29 and 29' permits them to swing as required by the opening and closing of the doors.

A compressed air conduit 39, 39', respectively, leads from each of the nipples 36 along the wall of the garage and into the pavement and has a lateral branch 40, 40' entering opposite sides of a coupling connected to the air control valve 55

42 which is located on the floor of the pit 10 and in a centralized position therein.

The control valve 42 comprises a casing 43 containing a working piston 44 having the piston rod 45 projecting through a removable top 46 closing the upper end of the casing and having therein an air outlet 47. The upper end of the piston rod 45 contains a ball 48 which is swivelly socketed by the socket arrangement 49 attached 10 to the lower side of the depressible platform 11 as shown in Figure 5, in such a way that the piston 44 will follow the rise and fall of the platform 11.

As shown in Figure 5 the T-coupling conduit 15 40 communicates with the interior of the casing 43 through an opening 50 and the casing has another opening 51 somewhat below the opening 50. It is also shown that the compressed air supply conduit 66 communicates with the interior of the casing 43 by means of a hole 52 in the opposite side of the casing. The piston 44 has a transverse passage 53 which connects the holes 50 and 52 when the piston is in a depressed position. The piston also has in one side an L-shaped opening 54 which registers with the opening 50 when the piston 44 is in an elevated position so that communication between the compressed air conduit 40 and the interior of the casing 43 is maintained despite the position of 25 the piston across the opening 50.

There are preferably four heavy coiled springs 55 in each of two longitudinally arranged rows under the platform 11 and seated on the floor of the pit 10 to keep the platform in its elevated position and to yield when the platform is pressed downwardly by the weight of an automobile or the like, and to return the platform to the elevated position after the weight has been released therefrom.

40. Blocks 56 are placed on the floor of the pit to limit the downward movement of the platform, while the platform has at each corner a depending leg 57 having rollers 58 thereon rolling against the vertical ends of the pit 10 for the 45 purpose of preventing the platform from becoming misaligned, and to ensure free and positive movement of the platform under all conditions of operation. If desired masks 59 of flexible or inflexible material may be provided to 50 bridge the gaps at the opposite ends of the platform between the ends of the platform and the corresponding end walls of the pit 10 so that the automobile will not be required to negotiate a bump in entering or leaving the garage, which 55 might cause undesirable jarring of the platform.

A spring bar 60 whose shape is clearly shown in Figures 1 and 2 is fastened as indicated at 61 over the outside of the doors and has an inwardly directed central part 62 adapted to be engaged 60 by upstanding rods 63 mounted on the upper ends of the inner edges of the doors 12 and 13. When the springs in the various hinges throw the doors to the closed positions these rods 63 strike the bar 60 as the doors come to the closed position, in such a way that the shock on the various hinges is relieved by the contact of the rods 63 with the spring 60, so that the doors can close quickly but quietly and without such jarring as would produce undue wear on the parts. If desired a suitable locking mechanism 64 may be cooperatively mounted on the doors for locking the same, although locking of the doors may be procured simply by cutting off the supply of compressed air to the cylinders 29, 29' which is 75 accomplished by closing the valve 65 which is in-

terposed in the compressed air supply pipe 66 which enters one side of the control valve 42 as shown. Any suitable source of compressed air or other fluid under pressure may be provided, such as a pressure tank, and this is the only motive force required for the operation of the doors. 5

With the platform in the elevated position shown in Figures 1 and 3 of the drawings, the rolling of an automobile upon the left hand end of the platform 11 will cause depression of the platform with consequent depression of the piston 44 in the control valve 42 to a position in which the side of the piston will close off the opening 50 leading to the piston supplying air pipes 39 and 39'. When the automobile progresses farther toward the doors the platform 11 will be farther depressed so as to bring the piston 44 into its lowermost position in which the passage 53 therein will bring the compressed air supply pipe 66 in communication with the pipe 20 40 which supplies the piston pressure conduits 39 and 39', whereby air under pressure will be entered in the cylinders 29 and 29' in front of the pistons 38 so as to drive the pistons toward the closed end of the cylinders, with the effect 25 of pulling the piston rods 28 and 28' outwardly so as to effect swinging of the doors in an upward direction from Figure 2 or in a left hand direction from the position of Figure 3 until the doors occupy the full open positions. 30

The platform is so proportioned in length that less of the platform is located within the garage than outside, so that the automobile need not travel an excessive distance within the garage in order to get off of the platform and permit 35 the same to return to initial elevated position. When the automobile has entered the garage and has left the platform 11, and the platform is returned toward the initial elevated position, the air above the piston 44 in the valve 42 will exhaust 40 through the opening 47, the air compressed below the piston will exhaust through the opening 51, and the spring hinges forcing the doors toward the closed position and pushing the pistons 38 45 backwardly in the cylinders 29 and 29', will exhaust the cylinders 29 and 29' back through the conduits 39 and 39', through the pipe 40 into the casing of the control valve below the piston 44 and out through the opening 51, so that little 50 resistance is offered to the springs in their door closing action. The described mechanism is then ready to operate for opening the doors as soon as the automobile has been backed onto the portion of the platform within the garage when it is desired to take the automobile out of the 55 garage. When in backing the automobile out of the garage the automobile leaves platform 11, the same will return to initial position, thereby permitting the doors to close after the automobile has left the garage. 60

Although I have shown and described herein a preferred embodiment of my invention, it is to be definitely understood that I do not desire to limit the application of the invention thereto, and any change or changes may be made in the materials, 65 and in the structure and arrangement of the parts, within the spirit of the invention and the scope of the subjoined claims.

What is claimed is:—

1. In a door construction of the class described 70 comprising a pair of doors hingedly mounted on a support and each door including a plurality of foldable sections, means for closing said doors and spring means mounted over each door and engageable by a portion of each door as the door 75

is swung into closed position so as to take up the shock of the closing of the door and prevent transmittal of the shock to the door closing means.

2. In a door construction of the class described comprising a pair of doors hingedly mounted on a support and each door including a plurality of foldable sections, means for closing said doors,

shock preventing means secured above each door comprising a spring member including a pair of arms diverging from the center of the doors outwardly and an upwardly extending pin on the inner-most section of each door slidable against its respective arms. 5

KENNETH JAMES O'HARA.
